(57) **CLAIM**

I claim the ornamental design for a speaker system for integrating into sofa structure, as shown and described.

DESCRIPTION

FIG. 1 is a top, front and side perspective view of a speaker system for integrating into sofa structure showing my new design;

FIG. 2 is a front elevational view thereof, the rear elevational view being identical thereto;

FIG. 3 is a side elevational view thereof, the elevational view of the opposing side being identical thereto;

FIG. 4 is a bottom plan view thereof,

FIG. 5 is a bottom, rear and side perspective view thereof; and,

FIG. 6 is a reduced perspective view similar to FIG. 1 showing the speaker system for integrating into sofa structure in use; the broken lines depict environmental structure for illustrative purposes only and form no part of the claimed design.
